UNITED STATES PATENT OFFICE.

WILLIAM R. DUTEMPLE, OF PROVIDENCE, RHODE ISLAND.

DESIGN FOR A PIN OR OTHER LIKE ARTICLE OF JEWELRY.

SPECIFICATION forming part of Design No. 15,236, dated August 12, 1884.

Application filed June 6, 1884. Term of patent 3½ years.

To all whom it may concern:

Be it known that I, WILLIAM R. DUTEMPLE, a citizen of the United States, residing at Providence, in the county of Providence and State of Rhode Island, have invented and produced a new and original Design for Gem-Settings; and I do hereby declare the following to be a full, clear, and exact description of the invention, reference being had to the accompanying drawings, and to letters or figures of reference marked thereon, which form a part of this specification.

The leading feature of my design consists in a pin or other like article of jewelry having a corrugated band extending around the center portion of a cylindrical setting, combined with two plain bands, one of which extends around the bottom edge and the other around the top edge of the setting, the latter band terminating in a notched or serrated edge. A peripheral groove is formed between each of the edge bands and the central corrugated band.

Figure 1 is a side elevation of my newly-designed setting. Fig. 2 is a front view of

the same with the gem removed, and Fig. 3 a vertical central sectional view.

A represents the setting complete, its general configuration being cylindrical. B is the corrugated band extending around the central portion thereof. *a a* are the plain raised bands, which extend around the edges of the setting, and *b b* are the grooves formed between said center band, B, and edge bands, *a*. The top or outer band, *a*, has a series of 35 points, *c*, extending around its edge, all as fully shown.

I claim—

The design for a gem-setting herein shown and described, consisting of the central corrugated band, B, peripheral grooves *b*, and plain edge bands, *a*, one of the latter terminating in a series of points, *c*, around the surface of the cylindrical setting.

In testimony whereof I have affixed my signature in presence of two witnesses.

WM. R. DUTEMPLE.
